UNITED STATES PATENT OFFICE.

JOHN L. E. PELL, OF GREAT BARRINGTON, MASSACHUSETTS.

GAME APPARATUS.

No. 808,111.

Specification of Letters Patent.

Patented Dec. 26, 1905.

Application filed January 12, 1905. Serial No. 240,676.

To all whom it may concern:

Be it known that I, JOHN L. E. PELL, a citizen of the United States, residing at Great Barrington, Massachusetts, have invented certain new and useful Improvements in Game Apparatus, of which the following is a clear, full, and exact description.

My invention relates to a game apparatus, particularly one which simulates a game of foot-ball; and my object is to improve and simplify the construction.

My invention will be set forth in the claims.

In the preferred embodiment of my invention shown in the drawings, Figure 1 is a perspective view of my playing-board with the play-pieces or men in position. Fig. 2 is a plan view of the same with the play-pieces arranged slightly differently. Fig. 3 is a section of Fig. 2 on the line *xx*. Fig. 4 is a front elevation, partly broken away, of one of the "line" men. Fig. 5 is a side view of the same. Fig. 6 is a front elevation of one of the "backs," and Fig. 7 is a side view of the same.

In carrying out my invention I provide a suitable playing-board, which, if desired, may be of the construction illustrated, which has an oblong frame consisting of side pieces 1 2 and shorter end pieces 3 and 4. If desired, each end piece may be pivoted to a side piece, as shown by the hinges 5 and 6, so that the frame may be easily folded together.

7 and 8 indicate suitable means for holding the parts in their opened or extended position, in this case consisting of a hook and eye.

35 The playing-field 9 may be of any suitable construction; but I prefer to use a green cloth, and, if desired, this may be suitably stretched by hooks 10 on the frame and a cord 11, which passes through suitable eyes in the cloth, as shown. The board is preferably marked with side lines 12 and 13 and transverse lines 14, which latter simulate the "five-yard" lines on a foot-ball field. At each end of the field goal-posts 15 and 16 may be provided, if desired.

40 The play-pieces or men comprise two sets, each preferably of eleven men, and the men of each set may have a common visual characteristic which is different from the men of the other set, so that the sets may be easily distinguished. In the embodiment shown in the drawings I have in Fig. 1 stippled the men of the set nearest to the observer and have left the men of the other set plain, while in

Fig. 2 the set at the left of the board is white 55 and those of the set at the right are dark colored.

17 and 18 represent one embodiment of a pair of supports, which are substantially parallel and extend over, preferably transversely 50 of, the board a short distance above the same. These supports may be in the form of wires, as shown, and are adapted to be moved over said board in a direction transverse to their length. In the present embodiment I have 55 suitably bent the wires, as shown at 19, and provided a foot 20, which will rest inside of the frame and upon the cloth, so as to hold the wire in whatever position it may be moved to. It will be obvious that the two wires 70 may be moved up and down the field. Depending from each of said supports is preferably a plurality of play-pieces or men. I prefer to have these play-pieces so constructed 75 that they are slidable on the support, 80 and they may also be pivoted to the support so as to swing below the same. In the embodiment shown in the drawings I have provided seven play-pieces for each support, each of which pieces is of the construction shown 85 in Fig. 5, the ring 21 being adapted to receive the wire support, by which the piece is both slidable upon the wire and pivoted thereon. I also prefer to form each of these pieces in sections and pivot the sections together. As shown in Figs. 4 and 5, the head 22 is pivoted to the body 23, and this in turn is pivoted to the legs 24. Preferably the pieces supported by the wire are of a length just sufficient so that the feet 25 of the man 90 will rest upon the cloth when the men are idly hanging from the support. Separate play-pieces 26 may be provided for each set—that is, pieces which are not attached to the supports. These pieces represent the backs. 95 One of them is shown in Figs. 6 and 7, and I may provide each or any of them with a recess 27, into which a separate play-piece or "ball" may be set as a convenient means of attaching the ball to such piece. These backs 100 26 are adapted to rest on the board and be freely slid along the same, and I prefer to provide each of them with a comparatively broad base 29, as by such a base the back may be snapped forward by the fingers of the 105 player and will slide along the board without easily upsetting.

In playing the game the two lines of men

held by the wires 17 18 are "lined up" opposite each other where the ball is supposed to be "down," as roughly indicated in Fig. 2. The player who has possession of the ball then attaches the ball to one of the backs and snaps him forward, endeavoring to make him pass through the lines of men, thus simulating a "line-bucking" play. The ball is down where the back stops. If the men hanging from the wires are slideable thereon, it will be obvious that a person playing on the defensive may mass his defense by moving his men together, thus "massing" his defensive play upon any one particular spot. The person who is playing on the offensive may also simulate a "tandem" play by placing two or three backs in line and snapping them forward together. The backs of the set which is on the defensive may be suitably placed to prevent "end runs," if desired; but the rules of the game may be widely varied, so as to as near as possible simulate the actual game of foot-ball.

I am aware that many variations from the construction shown may be made without departing from the spirit of my invention as claimed, and I therefore do not desire to limit myself to the embodiment illustrated in the drawings.

30. What I claim is—

1. In a game apparatus in combination, a playing-board, a pair of substantially parallel supports extending transversely of said board above the same and adapted to be moved over said board in a direction transverse to their length, each of said supports having depending therefrom a plurality of play-pieces, and one or more separate play-pieces adapted to rest on said board and be slid along the same.

2. In a game apparatus in combination, a playing-board, a pair of substantially parallel supports extending transversely of said board above the same and adapted to be moved over said board in a direction transverse to their length, each of said supports having depending therefrom a plurality of play-pieces slideable on said support, and one or more separate play-pieces adapted to rest on said board and be slid along the same.

3. In a game apparatus in combination, a playing-board, a pair of substantially parallel supports extending transversely of said board above the same and adapted to be moved over said board in a direction transverse to their length, each of said supports having swinging below the same a plurality of play-pieces, and one or more separate play-pieces adapted to rest on said board and be slid along the same.

4. In a game apparatus in combination, a playing-board, a pair of substantially parallel supports extending transversely of said board above the same and adapted to be

moved over said board in a direction transverse to their length, each of said supports having depending therefrom a plurality of play-pieces, some of said pieces being formed of sections pivoted together, and one or more separate play-pieces adapted to rest on said board and be slid along the same.

5. In a game apparatus in combination, a playing-board, a pair of substantially parallel supports extending transversely of said board above the same and adapted to be moved over said board in a direction transverse to their length, each of said supports having depending therefrom a plurality of play-pieces, and one or more separate play-pieces adapted to rest on said board and be slid along the same, each of said separate pieces having a broad base.

6. In a game apparatus in combination, a playing-board marked with parallel transverse lines, a pair of substantially parallel supports extending transversely of said board above the same and adapted to be moved over said board in a direction transverse to their length, each of said supports having depending therefrom a plurality of play-pieces, and one or more separate play-pieces adapted to rest on said board and be slid along the same.

7. In a game apparatus in combination, a playing-board, a pair of substantially parallel supports extending transversely of said board above the same and adapted to be moved over said board in a direction transverse to their length, each of said supports having depending therefrom a plurality of play-pieces, and one or more separate play-pieces adapted to rest on said board and be slid along the same, and a "ball" adapted to be attached to and carried by said separate piece.

8. In a game apparatus in combination, a playing-board marked with parallel transverse lines, a pair of substantially parallel wires extending transversely of said board above the same and adapted to be slid over said board in a direction transverse to their length, each of said wires having swinging below the same seven play-pieces slideable lengthwise on said support, each of said pieces being formed of sections pivoted together, and eight separate play-pieces adapted to rest on said board and be slid along the same and each having a broad base, and a "ball" adapted to be attached to and carried by at least two of said separate pieces.

9. In a game apparatus in combination, a playing-board, two sets of eleven men each, the men of each set having a common visual characteristic different from the men of the other set, whereby said sets may be distinguished, a plurality of men of each of said sets being shorter than the rest of said men and provided with a broad base whereby said

men may be snapped forward by the fingers of the player and slide along said board without easily upsetting.

10. In a game apparatus in combination, a playing-board, a plurality of substantially parallel supports extending over said board above the same and adapted to be moved over said board in a direction transverse to their length, play-pieces depending there-

from, and one or more separate play-pieces adapted to rest on said board and be slid along the same.

Signed at Great Barrington, Massachusetts, this 5th day of January, 1905.

JOHN L. E. PELL.
